UNITED STATES PATENT OFFICE

JOSEPH VAN ACKEREN, OF PITTSBURGH, PENNSYLVANIA, ASSIGNOR TO THE KOPPERS COMPANY OF DELAWARE, A CORPORATION OF DELAWARE

INTERMITTENT VERTICAL COKING RETORT OVEN

Application filed January 8, 1927. Serial No. 159,769.

My invention relates to vertical coking retort ovens and it has particular relation to vertical combination coke ovens of the intermittent type.

5 My invention has for one of its objects to provide a vertical coking retort battery in which the heat that is applied to the various levels of the retorts may correspond substantially to the amounts of coal to be coked at those levels.

A further object of my invention is to provide a heating system for vertical coking retort ovens wherein the heat is applied uniformly across the battery and is graduated throughout the height of the ovens in accordance with the amounts of coal at the various levels.

10 A further object of my invention is to provide means whereby the distribution of gas and air that is supplied upwardly to the several flue sections in a heating wall may be easily and conveniently controlled.

15 A further object of my invention is to provide an arrangement whereby sliding bricks may operate to regulate the flow of fluids upwardly from a horizontal passageway.

20 A further object of my invention is to provide an intermittent vertical oven that is equipped to employ either lean gas or rich gas as fuel.

25 A further object of my invention is to provide a supporting structure for a coke oven battery that effectually seals the bottom surface of the brickwork thereof and thereby prevents leakage of gas therethrough.

30 A further object of my invention is to provide a vertical coke oven battery with efficient closure means at the bottoms of the several retorts whereby the charges of material to be coked may be retained and the coke discharged easily and conveniently.

35 A further object of my invention is to provide closure means for the bottoms of vertical coking retort ovens that are gas-tight and which are sealed automatically upon their return to closed positions.

40 A still further object of my invention is to provide simple and efficient means for regulating the individual supplies of gas and air to the flame flues of a coke oven battery.

In intermittent vertical coking retort ovens, it is essential that the retorts be somewhat wider at the bottom than at the top in order that the coke may be removed therefrom by gravity when the bottom closure is removed. As an incident to this construction, the amount of coal to be coked at the top of the oven is small relatively to that at the bottom by reason of the differences in width.

45 If a uniform quantity of heat were applied throughout the entire height of the oven, the coal at the top would be coked before that at the bottom, as will be readily appreciated. It is desired, therefore, to heat the ovens uniformly across the battery, but to graduate the heat that is applied from the bottom of the oven to the top thereof substantially in accordance with the amount of coal at the various levels therein.

50 In accordance with the present invention, I divide the flame flues of a vertical coking retort oven of the intermittent type into sections whereby gas and air may be supplied at different points in the flame flues in order to effect a desired distribution of heat from the bottom to the top of the wall. The products of combustion of the primary flues are employed to dilute the fuel and air supplied to the secondary flue sections in order that there may be no concentration of heat at the bottom portions of the secondary flue sections and less fuel is supplied to the latter sections in order that the heat developed in them may be less than that in the primary flue sections. The secondary flue sections are slightly larger than the primary flue sections in order that substantially uniform velocities of the products of combustion may obtain throughout the height of the heating walls.

55 It has been proposed heretofore to provide vertical coke ovens with closures that were bodily removable but which required door-handling machines and, in addition, it was necessary to seal the doors by luting, as in connection with horizontal ovens. Such doors have proven to be cumbersome and difficult to handle and, in addition, it was difficult to remove the doors and to successfully handle the falling coke. Much time is also required to remove and replace the

doors and to render them gas-tight before the ovens were again charged.

In the battery embodying my invention, the bottoms of the ovens are controlled by 5 rotatably mounted closure devices that are mechanically operated to their respective open or closed positions without removal from beneath the battery. Means are provided whereby the doors are automatically 10 sealed in a gas-tight manner when they are actuated to their closed positions.

I provide, also, improved means for regulating the flow of preheated air and preheated lean gas to the several sections of the flame 15 flues. Sliding bricks are provided in such manner that they may regulate the quantity of preheated air or preheated gas that is supplied upwardly to each section of the flame flues.

20 My invention will be described in connection with the accompanying drawings, in which similar reference numerals are employed to designate corresponding parts.

Figure 1 is a view, in transverse vertical 25 section, of a coke oven battery constructed in accordance with my invention, the view being taken through one of the coking chambers;

Fig. 2 is a view, in transverse vertical section, through one of the heating walls of the 30 coke oven battery;

Fig. 3 is a view, in longitudinal vertical section, of a portion of the coke oven battery of Fig. 1, parts being broken away;

Fig. 4 is a view, in broken horizontal section, taken on the line IV—IV of Fig. 3;

Fig. 5 is a view, in vertical section, through a pair of the regenerators taken on the line V—V of Fig. 1;

Fig. 6 is a view, in horizontal section, taken 40 on the line VI—VI of Fig. 5;

Fig. 7 is an enlarged sectional view on line VII—VII of Fig. 8 of certain of the horizontal flues and their connections to the corresponding regenerators;

Fig. 8 is a sectional view, taken on the line VIII—VIII of Fig. 7;

Fig. 9 is a sectional view, taken on line IX—IX of Fig. 7;

Fig. 10 is a sectional view, taken on the 50 line X—X of Fig. 11, of one of the closures and its associated apparatus, parts being broken away; and

Fig. 11 is a transverse sectional view, taken on the line XI—XI of Fig. 10.

55 Referring particularly to Fig. 1, a coke-oven battery comprises a foundation 1, supporting columns 2, a supporting wall 3 and a main oven structure comprising side walls 4 and 5 that rests upon the wall 3 and a beam 6 on the columns 2. The sides of the battery are provided with buck-stays 7 that are held together by means of tie rods 8 and plates 9.

Extending between the walls 4 and 5 are 60 vertical coking retorts 11 of any convenient or desired number, through one of which

the sectional view is taken and, also, heating walls 12 that alternate with the retorts 11. A larry car 13, that is supported on rails 14 on the oven top 15, operates to charge the several coking retort ovens 11.

70 A gas offtake 16, that is located at the top of each retort of the battery, is connected to a collecting main 17. Each retort is provided, also, with a pressure-relief opening 18 at the bottom thereof and that is connected through a pipe line 19 to a main 20. Regenerators 22 that co-operate with the heating systems of the several heating walls 12 are located along the supporting wall 3 and below the main oven structure. The regenerators 22 are provided with sole channels 23. Producer gas or other lean gas is supplied from a gas main 24 having suitable regulating valves 25 at each outlet therefor. A main 26 conducts waste gases to the stack. Each retort 11 is provided with a closure mechanism 27, the details of which will be later described. A car 28 receives the coke from the several retort ovens.

80 Reference may now be had to Figs. 2, 3, 4, 5 and 6, in which certain structural details of the coke oven battery are illustrated. Each of the retorts 11 comprises a relatively narrow vertical passage of elongated cross-section and tapering between adjacent heating walls 12, the greater width being at the bottom in order to facilitate the removal of coke by gravity at the completion of the 85 operation. Each retort chamber is provided with a central charging opening 30.

90 Each heating wall 12 is provided with vertical heating flues, divided into lower or primary sections 33 and upper or secondary sections 34 that are in vertical alinement and are sufficiently closely adjacent that each of the alined upper and lower sections together 95 constitute a substantially continuous heating flue. The upper or secondary flue sections are wider than the lower sections for reasons previously stated. The number of heating flues may be in accordance with the horizontal length of the walls 12, five being shown by way of example in the structure 100 illustrated herein. As shown in Fig. 4, each of the heating flues is substantially rectangular in cross-section, the end portions of which, in the case of the primary sections 33, are slightly wider than the intermittent portions. The closely adjacent ends of the 105 upper and the lower sections are formed by an intermediate or horizontal brickwork 35, through which the primary and secondary sections are connected and through which the secondary sections are supplied with gas and air, as will be later described.

110 The flue system of each of the heating walls is operatively connected by means of lower horizontal flues 36 and 37 to two regenerators 120 22 of the usual checkerwork type, one of which appears in Fig. 1. When producer 125

gas, or other lean gas is employed as a fuel, one of the horizontal flues conveys preheated gas and the other conveys preheated air to both the upper and the lower sections of the several heating flues of each wall in which gas is being burned.

As will be noted in Fig. 3, each of the horizontal flues 36 and 37 is substantially directly connected through suitable ports to each of the lower or primary flue sections 33. The horizontal flues 36 and 37 are also connected to the upper flue sections 34 by means of ducts 38 that extend between and closely parallel the lower sections 33.

Alternate ducts 38 are connected to the horizontal flue 36 and the other ducts 38 are connected to the horizontal flue 37. As is shown in Fig. 2, each of the ducts 38, except the end ones, have branches 39 connected to two of the upper flue sections 34, the branches 39 being located in the horizontal brickwork 35. By means of this arrangement, each of the upper flue sections is supplied with preheated fuel and preheated air by the employment of a minimum number of ducts 38.

Each of the openings leading from the horizontal flues 36 and 37 to the lower flue sections 33 and to the ducts 38 is controlled by a sliding brick 41 that is located in a groove 42, immediately above the corresponding horizontal flue. Certain of these bricks appear in Figs. 3 and 8. The positions of the sliding bricks 41 may be adjusted through openings 43 in the side wall 5, the openings being ordinarily closed by removable bricks 44. The positions of the sliding bricks 41 control the distribution of air and gas to the several flues within each heating wall.

In case coke oven gas or rich gas is employed as a fuel, it is supplied, without pre-heating, to each series of flue sections by means of gas guns 45 of usual construction that are respectively connected to the bottom portions of each of the flue sections. The gas gun for supplying the upper flue sections extends through the horizontal brick-work 35. The gas guns 45 for supplying the lower flue sections are suspended beneath the floors of the heating walls and are connected, by vertical pipes 46, to the bottom portions of the corresponding flue sections. The latter arrangement is clearly shown in Fig. 3.

The products of combustion from the lower flue sections 33 pass upwardly through ducts 48 in the horizontal brickwork into the secondary sections 34. The combined products of combustion of the lower and the upper flue sections of each wall pass upwardly into an upper horizontal flue 49, the openings into which are controlled by sliding bricks 50 that are seated in a groove 51 in the lower portion of the flue 49. The bricks 50 also control indirectly the distribution of the heating since

they control the flow of products of combustion. The positions of the sliding bricks 50 may be regulated through inspection openings 52 through the top of the battery. The upper horizontal flues 49 of co-operating heating walls 12 are connected by two cross-over flues 53, which extend above the top of the intervening retort 11. The flue systems of the heating walls are accordingly connected in pairs. The cross-overs 53 are located on opposite sides of the charging opening 30.

Reference may now be had to Figs. 1, 5, 6 and 8, in which certain details of the construction of the regenerators 22 and their connections to the corresponding horizontal flues 36 and 37 are illustrated. The regenerators 22 are arranged in pairs with the exception of the end regenerators which are a single unit inasmuch as they supply a single horizontal flue. The regenerators 22 are each provided at the top thereof with a duct 55 that is connected to the corresponding horizontal flue by means of a curved metal pipe or elbow 56 that is lined with refractory material having two ducts 57 therethrough for a pair of regenerators. The ducts through the pipe 56 are connected to ducts 58 that extend through the wall 4 and are connected to the ends of the corresponding horizontal flues 36 and 37. The pipe 56 is provided with flanges 59 that engage the buck-stays 7 and are connected thereto in any suitable manner, as by rivets or welding. The spaces between the buck-stays 7 to which the pipe 57 is attached are filled with suitable refractory material, cores being inserted initially to provide the passageways therethrough.

By referring to Fig. 8, it will be noted that the pairs of regenerators are not connected to corresponding pairs of horizontal flues 36 and 37, but are connected to flues of different heating walls. This arrangement is provided in order that both members of each pair of regenerators are being traversed simultaneously either by gas, air or waste gases. In other words, each member of a pair of regenerators is under exactly similar operating conditions.

Reference may now be had to Figs. 10 and 11, in which the details of the closure mechanism 27 for one of the retorts 11 are shown in enlarged detail. Beneath each retort 11 and surrounding the bottom opening thereof are flanged hollow castings 60 that extend into, and are supported by, the concrete beam 6 on the tops of the columns 2 and by the wall 3. The castings 60 constitute supporting frames for the bottom of the oven structure. The joints between the side flanges of adjacent supporting frames 60 are sealed, for example, by pitch and asbestos rope whereby the entire bottom surface of the brickwork is covered and leakage of gas through the joints thereof is prevented.

In addition to the anchorage in the wall 3

and beam 6, tie rods 61 that extend beneath the battery also tend to support and maintain the frames 60 in their positions. Castings 62 are also anchored respectively to the supporting wall 3 and to the concrete beam 6 and are provided with eye-bolts 63 that are pivotally connected thereto.

The door mechanism comprises an elongated frame structure 64, of trough shape, having outwardly extending lugs 65 at the corners thereof for connection to the eye-bolts 63 by means of which it is supported. The frame 64 has parallel and continuous outer and inner walls 66 and 67 that form a relatively deep trough upon the left side of the frame 64, as viewed in Fig. 11, and the ends of the frame 64 and a relatively shallow trough upon the opposite side. The central portion of the frame 64 is open.

An elongated door 68, the outer surface of which constitutes a portion of a cylinder and having segmental end portions 69, is rotatably supported on the ends of the frame 64 by means of bearing members 70 and 71, to which the door 68 is rigidly secured. The member 71, which is in the form of a short shaft, is connected to a shaft 72, only a portion of which is shown, and which may be connected to any suitable power device (not shown) for operating the door 68.

The entire closure mechanism 27 comprising the frame 64 and its connected parts may be removed as a unit by first supporting the frame 64 while the nuts 73 are removed from the eye-bolts 63. The eye-bolts swing to vertical positions and permit the withdrawal of the entire closure mechanism. The latter may be assembled by reversing the operations.

The trough constituted by the interior and exterior walls of the frame 64 permits the door 68 to be rotated to the left from its illustrated or closed position, the deep trough receiving the side of the door and the shallow portion of the trough receiving the opposite side of the door when in its illustrated or closed position.

The trough is filled with ammoniacal liquor that is supplied through sprays 74 for removing any tar that may flow from the retort 11 upon the outer surface of the door 68. Suitable drains 75 are provided for withdrawing the contents of the trough when desired. A gas-tight connection between the retort 11 and the liquid seal afforded by the ammoniacal liquor is insured by a casing 76 of substantially rectangular shape that extends below the level of the ammoniacal liquor and is connected to an annular plate member 77, having upwardly curved ends conforming to the door 68, both of these members being secured to the frame 60.

The lower side of the hollow portion of the frame 60, which surrounds the retort 11,

is closed by the members 76 and 77 to provide an annular chamber 78 or water jacket that is supplied with cooling water by means of inlet pipes 79. Outlet pipes 80 are also provided.

The supporting frames or castings 60 are of sufficient mechanical strength that they support the brickwork of the oven structure between the concrete beam 6 and the supporting wall 3. This arrangement renders unnecessary the provision of supporting beams or other intermediate framework that has been used heretofore. In addition, there is no exposed brickwork on the bottom of the oven and leakage of gas through the brickwork is effectually prevented by the upper surfaces of the supporting frames 60 and the substantially gas-tight joints therebetween.

Expansion of the foundation structure is substantially prevented by the cooling system constituted by the water-filled chambers 78 that surround the bottom opening of each of the retorts and operate to maintain the supporting castings and the lower portion of the brickwork at a comparatively low temperature. The layer of coke breeze in the bottom of each coking chamber operates, also, to insulate the door mechanism and the lower brickwork from the hot charge above and thus assists in maintaining relatively low temperatures beneath the battery. Further, expansion joints may be provided between the frames 60 and their supports whereby any expansion of the frames is compensated. Consequently, there is no danger of damage to the supporting foundations and structure by reason of expansion while the battery is in operation.

It may be assumed that the battery has been brought to operating temperature and that it is desired to start the coking operations. The charging operation will be described in connection with one of the retorts 11, the same procedure being followed in connection with the remainder of the retorts. The door 68 of the oven to be charged is in its closed position, as illustrated in Figs. 10 and 11. The larry car 13 then discharges a sufficient quantity of coke breeze through the charging opening 30 of the oven to be charged that it fills the bottom portion of the oven to a height substantially corresponding to the bottoms of the flame flue sections 33. The coke breeze is provided in order that all of the coal to be coked may be in contact with the wall that is subjected to the heat evolved in the flame flues. The larry car is next operated to discharge a sufficient amount of coal to fill the retort 11 to the desired level and the charging opening 30 is thereupon closed.

The ovens are heated with cold, clean producer gas that enters the heating system from the main 24 through metal regulating valves

25, the sole flues 23 of certain of the regenerators, then through the regenerators 22, ducts 57 and 58 into the horizontal flues 36 and 37.

Air also traverses similar paths through other 5 pairs of regenerators 22 into the corresponding horizontal flues 36 and 37. Preheated gas and air are supplied to the bottom portions of certain of the primary flue sections 33 to supply heat to the heating walls 12.

10 The products of combustion from the primary flues 33 pass upwardly through the ducts 48 in the horizontal brickwork 35 and into the bottom portion of the secondary flue sections 34. Preheated producer gas and preheated air are also supplied to the bottom portions of the secondary flue sections 34 by the ducts 38 and the branch ducts 39 in the horizontal brickwork 35. This arrangement insures that there will be no concentration of 20 heat at the bottom portion of the secondary flame flues 34, since the combustible gas is diluted at these points by the waste gases of the primary flue sections. It is desirable that less heat be applied to the coal to be coked in 25 the upper portion of the retort by reason of the relatively narrow width of the retort and the correspondingly smaller amount of coal to be coked. This arrangement, therefore, enables the heat to be applied in accordance 30 with the relative amounts of coal from the bottom to the top of the retorts. In other words, the heat applied to the retort 11 is tapered substantially in accordance with the shape of the retort.

35 The combined products of combustion of the primary and the secondary flue sections pass upwardly into the upper horizontal flue 49 that extends along the top of each heating wall and thence through the cross-over flues 53 into the upper horizontal flue 49 of an associated heating wall. The highly heated products of combustion then pass downwardly through the secondary flue section 44, the ducts 48 and the primary flue sections 33 into the horizontal flues 36 and 37, from which they flow through the pair of regenerators connected thereto into the waste gas main 26, which is connected to the stack.

50 The operation described above is typical of that of each pair of co-operatively associated heating walls. The direction of flow of gases in the associated heating walls is reversed at desired intervals in order that the heat stored in the regenerators 22 by the products of combustion may be utilized in preheating air and gas for the succeeding period.

55 During the process of coking, gas is evolved and fluid pressure will be exerted upon the bottom of the oven. Accordingly, the ammoniacal liquor between the sides of the door 68 and the casing 76 is depressed substantially as illustrated in Figs. 10 and 11 until the head of the liquor in the remaining portion 60 of the trough equals the fluid pressure exert-

ed by the gas. The gas in the oven passes out the offtake 16 into the main 17.

When the coal within one of the retorts 11 is completely coked and it is desired to remove the same, the door 68 at the bottom thereof is operated through the shaft 72 to the left, as viewed in Fig. 11, the deep portions of the trough receiving the side and ends of the door. The coke then falls by gravity through the open space between the deep and the shallow trough portions into the coke-receiving car 28. When the coke is entirely removed, the door 68 is operated to its illustrated or closed position, in which it is again sealed in a gas-tight manner by the ammoniacal liquor. The oven may then be filled in the manner previously described—first, by the introduction of coke breeze and then with the charge of coal.

When the coke is dumped upon the usual coke wharf, the breeze may be screened out and a sufficient quantity retained to supply the amounts required in charging the ovens.

The heating of the coke oven battery has been described in connection with the use of producer gas that has been cooled and cleaned and is supplied through metal valves which insures that the heating system will not be clogged by dirt or residue that is incident to producer gas that is supplied directly to the battery. However, if desired, coke oven gas or other rich gas may be employed as a fuel, since the battery is supplied with gas guns 45, by means of which rich gas may be supplied to the bottom portions of each of the primary flue sections 33 and the secondary sections 34.

When rich gas is employed, all of the regenerators are traversed either by air or by waste gases in accordance with the direction of flow. The flow of gases in the heating system is substantially similar to that described in connection with producer gas, the products of combustion of the primary flue sections diluting the fuel gas and air that is supplied to the secondary flue sections in order that there may be no heat concentration adjacent to the horizontal brickwork. By means of this arrangement, the battery may be underfired by a portion of the gas that is collected in the main 17 or, in case it is desired to utilize the entire output for other purposes, producer gas may constitute the fuel.

The coke oven battery embodying my invention provides a heating system in which the heating is uniform throughout the width of the battery and is diminished from the bottom toward the top of the retorts in order that the heating may correspond substantially to the quantities of coal to be coked at the various levels.

The provision of cross-overs for connecting the horizontal flues improves the distribution of the gases by substantially eliminating horizontal travel of the gases. The products

of combustion of the series of flue sections of each heating wall are combined before they enter the regenerators and there is, accordingly, maximum exchange of heat between the waste gases and the air in the regenerators.

The supporting structure is so arranged that expansion is substantially eliminated by the cooling arrangement for maintaining the temperatures thereof at relatively low values.

10 The supporting structures effectually seal the bottom of the brickwork of the oven and leakage of gas with the attendant warping of metal structures is avoided.

15 The arrangement of the regenerators on a foundation independent of that of the battery structure permits the foundations to be simpler and cheaper by reason of the reduction in weight to be supported thereby. An additional advantage resides in the fact that 20 any expansion of the regenerators is entirely independent of that of the oven structure and no expansion joints therebetween are necessary.

25 The disposition of the regenerators with their outlets closely adjacent to the horizontal flues that are supplied thereby permits the gas to travel substantially a minimum distance, since the horizontal flues must be located in the bottom of the oven structure because up-burning is necessary in order to 30 secure tapered heating that diminishes progressively upward. The short travel of the gas diminishes the resistance to its flow through the over structure.

35 The provision of inspection openings at the top of the battery and of the ducts through the horizontal brickwork for connecting the aligned upper and lower flue sections enables the operator to observe conditions at any height of the heating walls.

40 While I have shown and described the various features of my invention in connection with intermittent vertical coking retort ovens, it will be appreciated by those skilled in the art that the application of my invention is not limited thereto. Various modifications of my invention may occur to others and it is understood, therefore, that my invention is not limited to the specific embodiments shown and described herein, but may be variously embodied within the scope of the claims.

I claim as my invention:

45 1. In a coke oven battery, the combination with a vertical coking chamber that gradually widens from the top to the bottom thereof, of a heating system therefor comprising vertical heating flues in superposed rows and means for supplying fuel to the rows of flues in such quantities that the heat applied to 50 said coking chamber gradually diminishes with the height thereof.

55 2. In a coke oven battery, the combination with a vertical coking chamber that gradually widens from the top to the bottom thereof,

of a heating system therefor comprising heating flues in superposed rows that are connected by passageways and means for supplying fuel to the bottom portions of the several flues in quantities substantially proportional to the corresponding or adjacent widths of the coking chamber.

60 3. In a coke oven battery, a series of alternating coking chambers and heating walls therefor, each heating wall comprising a plurality of vertical flame flues in superposed series, two lower horizontal flues for supplying fuel and air to the bottom portions of each of said flues for up-burning therein a single upper horizontal flue connected to the upper flues and a plurality of flues for connecting the upper horizontal flues in pairs.

65 4. In a vertical coke oven battery, the combination with a coking chamber, of a heating wall adjacent thereto having vertical flame flues, horizontal flues beneath said flame flues and connected thereto and means for operatively connecting the upper ends of said flame flues, and regenerators below the level of said heating wall and equal in number and substantially directly connected to said horizontal flues.

70 5. In a vertical coke oven battery, the combination with a main oven structure having a series of vertical coking chambers and vertical heating walls alternating therewith that are provided with flame flues and horizontal flues therebeneath and connected thereto, of regenerators outside and below the level of said main oven structure equal in number to that of said horizontal flues and so positioned with respect to said horizontal flues that they are substantially directly connected thereto.

75 6. In a vertical coke oven battery, the combination with a main oven structure comprising a series of heating walls and coking chambers alternately disposed, said heating walls having horizontal flues in the lower portions thereof and having also combustion flues connected to said horizontal flues, of regenerators supported independently of said main oven structure and having their top portions closely adjacent to said horizontal flues and equal in number and substantially directly connected to the respective horizontal flues.

80 7. In a vertical coke oven battery, the combination with a main oven structure comprising a series of heating walls and coking chambers alternately disposed, said heating walls having flame flues and horizontal flues beneath said flame flues and connected thereto, of regenerators respectively connected to one of said horizontal flues supported independently of said oven structure in such manner that the top portions of said regenerators are closely adjacent to one end of said horizontal flues and are respectively connected to the horizontal flues by passageways, the

number of regenerators being equal to that of said horizontal flues.

8. In a vertical coke oven battery, the combination with a series of alternately disposed coking chambers and heating walls having superposed rows of vertical flame flues therein, of means comprising horizontal flues for conveying lean gas and air to said flame flues, passageways extending horizontally through said walls for supplying rich gas to the upper flame flues and passageways extending vertically through the bottom of said battery for supplying rich gas to the lower flame flues.
- 15 9. In a vertical coke oven battery, the combination with a series of alternately disposed coking chambers and heating walls having superposed rows of vertical flame flues therein, of means comprising bottom horizontal flues for conveying lean gas and air to said flame flues and passageways extending vertically through the bottom of said battery and other passageways extending horizontally in said heating walls for supplying rich gas to the rows of flame flues, respectively.

In testimony whereof, I have hereunto subscribed my name this 3rd day of January, 1927.

JOSEPH VAN ACKEREN.
